DESIGN FOR A TABLE

Abraham Hartman, New York, N. Y., assignor to
H. & K. Furniture Co., Inc., New York, N. Y.,
a corporation of New York

Application January 17, 1939, Serial No. 82,398

Term of patent 3½ years

To all whom it may concern:

Be it known that I, Abraham Hartman, a citizen of the United States of America and resident of New York city, county of Bronx, and State of New York, have invented a new, original, and ornamental Design for Tables, of which the following is a specification, reference being had to the accompanying drawing, forming part thereof.

In the drawing:

Figure 1 is an end elevational view of a table showing my new design.

Figure 2 is a view in perspective, on an enlarged scale, of the table shown in Figure 1.

Figure 3 is a side elevational view as seen from either side of Fig. 1.

I claim:

The ornamental design for a table, as shown.

ABRAHAM HARTMAN.
